UNITED STATES PATENT OFFICE.

FALCONOR GIFFARD, OF BURLINGTON, IOWA, ASSIGNOR OF THREE-FOURTHS
TO WM. PENROSE AND SOLOMON MCNEILL, BOTH OF SAME PLACE.

CARTRIDGE DECAPPER, RECAPPER, AND RELOADER.

SPECIFICATION forming part of Letters Patent No. 294,865, dated March 11, 1884.

Application filed July 30, 1883. (Model.)

To all whom it may concern:

Be it known that I, FALCONOR GIFFARD, a citizen of the United States, residing at Burlington, in Des Moines county, and State of Iowa, have invented a new and useful Improvement in Cartridge Capping, Decapping, and Loading Devices, which is fully set forth and described in the following specification, reference being had to the accompanying drawings, 10 in which—

Figure I is a perspective view of the entire device. Figs. II and III are views of the handles. Fig. IV is a vertical sectional view of the decapping device from end to end. Fig. 15 V is an enlarged cross-section through one of the handles, showing the capping device.

Similar letters indicate similar parts.

The object of my invention is to furnish a set of devices for capping, decapping, and 20 loading cartridge-shells, which are preferably put, for convenience and safety, into a single tool, in which the necessary force is applied by means of levers, thus avoiding such violence as would explode the cap. I accomplish this 25 by hinging two handles, B and C, to two shell-chambers, F and G, in piece A, thus securing a leverage over the shells in the chambers.

In the handle B is a perforation, e, through which the cap escapes.

30 The capper is a pin or anvil, n, in the center of a recess, R, in handle B, around which a washer, m, plays, and is forced out by a spiral spring, l, from behind it, thus forming a cavity over the pin n to receive the cap, 35 hold it in place, and conduct it to the cavity in the shell. When the handle is pressed inward, the washer recedes on the spring, and the pin n forces the cap into place in the shell. The cap being fixed, the load is put into the 40 shell from the opposite end, and the wads are placed in position by the use of the ramrod, b,

which is hinged at its upper end in handle C, opposite the mouth of the shell-chamber F, and is folded within the handle C when not in use.

45 The decapper M consists of a rod, d, of any suitable material, provided with a shoulder, f, and placed inside an interior shell, g, preferably of wood. A spiral spring, e, is placed upon the rod d, which is provided at its end with the ejector-pin h, to force the cap from the cartridge-shell through the perforation e.

I claim and desire to secure by Letters Patent—

1. The combination, in a cartridge implement, of the cartridge-chambers F G, their support A, and handles B and C, hinged thereto, the handle B having recessed chamber wherein is supported a fixed capping-anvil surrounded by a spring-actuated washer, which 60 normally projects beyond said pin, forming a recess for the support of the primer, and the handle C provided with means for forcing the cartridge against the capping-anvil, all substantially as described. 65

2. The combination of the handle B, having cap-escape perforation e, and the handle C, both hinged to the support A of the decapping-chamber G, said chamber and the decapper M, located therein, having spring-actuated ejector-pin, all substantially as described. 70

3. In a cartridge implement, the combination of the handles B and C, hinged to a chamber-support, A, the handle C bearing hinged ramrod b, and the handle B having the capper a, said ramrod and capper located opposite the ends of shell-retaining chamber F in support A, all substantially as described. 75

FALCONOR GIFFARD.
